(57) **CLAIM**

The ornamental design for an illuminated device case for electronic communications device, as shown and described.

DESCRIPTION

FIG. 1 is a perspective view of the illumination device according to a first embodiment.

FIG. 2 is a front view of the illumination device as shown in FIG. 1.

FIG. 3 is a back view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is a perspective view of the illumination device according to a second embodiment.

FIG. 9 is a front view of the illumination device as shown in FIG. 8.

FIG. 10 is a back view of FIG. 8.

FIG. 11 is a left side view of FIG. 8.

FIG. 12 is a right side view of FIG. 8.

FIG. 13 is a top view of FIG. 8.

FIG. 14 is a bottom view of FIG. 8.

FIG. 15 is a perspective view of the illumination device according to a third embodiment.

FIG. 16 is a front view of the illumination device as shown in FIG. 15.

FIG. 17 is a back view of FIG. 15.

FIG. 18 is a left side view of FIG. 15.

FIG. 19 is a right side view of FIG. 15.

FIG. 20 is a top view of FIG. 15; and,

FIG. 21 is a bottom view of FIG. 15.

The illuminated case for electronic communications device is shown with symbolic breaks in its length and width. The appearance of any portion of the article between the break lines forms no part of the claimed design. The dot dash break lines are for the purpose of illustrating the breakaway, and form no part of the claimed design.
